UNITED STATES PATENT OFFICE.

STERLING H. CAMPBELL, OF ST. LOUIS, MISSOURI, ASSIGNOR TO RAILWAY DEVICES COMPANY, OF ST. LOUIS, MISSOURI, A CORPORATION OF MISSOURI.

COUPLER-RELEASE RIGGING.

Application filed May 18, 1925. Serial No. 31,095.

My invention relates to a coupler release rigging and particularly to that type of rigging in which a pivoted operating or hand lever is employed.

One object of my invention is to so construct the device that the lifting lever will be independent of the operating lever so that the former is free to move in response to the movement of the coupler head without 10 in any way affecting the latter.

Another object of my invention is to provide the operating lever with two gripping portions in different horizontal planes so that it may be readily operated either by a person 15 standing on the ground or by one on the car.

In the accompanying drawings, which illustrate two forms of release rigging made in accordance with my invention, Figure 1 20 is a perspective view of the end of a car embodying my preferred form of rigging; Figure 2 is a sectional view showing the relative positions of the operating and lifting levers; and Figure 3 is a perspective view 25 showing a modification.

Referring first to Figures 1 and 2, the body of the car, indicated at 5, is provided with the usual end sill 6 carrying the coupler head 7 controlled by lock pin 8. On the 30 end sill 6 is the hand hold 9 in the usual manner. All these parts may be of any usual construction.

Secured to the end sill 6 at about the center of its length is a bracket 10 having an 35 upwardly extending pair of lugs 11 between which is pivoted, at point 12, the pin lifting lever 13 the end of which is connected with the lock pin 8 by a link 14. As shown, this link is provided at its lower end with 40 an enlarged head 15 to prevent its disengagement from the eye of the lock pin, and it is retained in the horizontal eye of the lifting lever by a nut 16. Other forms of link may be used to connect the lifting lever 45 with the lock pin, as for example that shown in Figure 3. It is to be noted, however, that a one-piece link without sliding movement may be used in construction because the lifting lever is independent of the operating lever except when the pin is being lifted.

Carried by the bracket 10 is a second pair of lugs 17 arranged at right angles to the lugs 11 and having pivoted between them, at point 18, the inner end of operating lever 50 19. The operating lever is supported by an

extension 20 on the bracket 10, said extension being provided with a retaining lip 21 for limiting lateral movement of the lever. Lever 19 extends to a point adjacent to the side of the car in a nearly straight line and is 60 there provided with a hand piece or grip 22, by means of which the lever may be lifted to raise the lock pin by a person on the car, e. g. on the hand hold 9. Beyond the grip 22 the lever is provided with a downward 65 extension 23 terminating in a second hand piece or grip 24, by means of which the lever may be lifted by a person standing on the ground.

In Figure 3 I have shown a modified form 70 of my device. In this modification the link 14 is replaced by a link 14^A having at each end a loop similar to the loop shown and described in Patent No. 1,226,859, granted to me May 22, 1917. The operating lever 19^A is 75 also differently shaped; in place of extending across the car in a nearly straight line it is bent downwardly and is provided at its lowest point with a straight portion 25 which forms a hand hold corresponding with 80 the grip 24 of the lever first described. Beyond the grip 25 the lever has an upwardly extending portion 26 terminating in a handle 27 corresponding to the grip 22 on the first 85 form of lever.

Where in the specification and claims I have used the term "pivoted operating lever" I wish to be understood as limiting the structure to one in which the lever moves bodily on a fulcrum in distinction from that in 90 which a rock shaft rotates on its axis.

Having fully described my invention, what I claim as new and desire to secure by Letters Patent of the United States is:

1. In a device of the class described, the 95 combination with a coupler lock pin, of a lifting lever connected with said pin, and operating lever pivoted adjacent to its inner end, whereby when lifted it is adapted to strike said lifting lever to elevate the pin. 100

2. In a device of the class described, the combination with a coupler lock pin, of a lifting lever extending in the direction of the length of the car and connected with said pin, and a pivoted operating lever extending 105 substantially at right angles to said lifting lever, said operating lever being adapted to strike said lifting lever to elevate the pin when its outer end is raised.

3. In a device of the class described, the 110

combination with a coupler lock pin, of a bracket, a lifting lever carried by said bracket and connected with said pin, and an operating lever also carried by said bracket and pivoted to move in a vertical plane, said operating lever extending below said lifting lever in a non-parallel direction.

4. In a device of the class described, the combination with a coupler lock pin, of means for raising said pin, a pull-up operating lever for actuating said raising means, said operating lever being provided with two handles arranged in different horizontal planes.

5. In a device of the class described, the combination with the end sill of a car, of a coupler provided with a lock pin, a lifting arm connected to said lock pin, a pull-up operating lever having two handles, one arranged above the other below said end sill.

6. In a device of the class described, the

combination with a coupler lock pin, of a lifting lever connected with said pin, and a pivoted pull-up operating lever extending under said lifting lever in a non-parallel direction, said operating lever having two handles arranged in different horizontal planes.

7. In a device of the class described, the combination with the end sill of a car, of a coupler lock pin, means for raising said pin, and an operating lever pivoted to move in a vertical plane for actuating said raising means, said lever having adjacent to the side of the car, a portion extending above the end sill and forming a handle and a portion projecting below the end sill and forming a second handle.

In testimony whereof, I have hereunto set my hand this the 15th day of May, 1925.

STERLING H. CAMPBELL.
